UNITED STATES PATENT OFFICE.

GUSTAVE E. VILLARET, OF LEONIA, NEW JERSEY, ASSIGNOR TO MARTEL ELECTRIC PRODUCTS, INC., OF BUFFALO, NEW YORK, A CORPORATION OF NEW YORK.

DESIGN FOR AN ELECTRIC-LIGHT FIXTURE.

Application filed January 21, 1929. Serial No. 29,701. Term of patent 3½ years.

To all whom it may concern:

Be it known that I, GUSTAVE E. VILLARET, a citizen of the United States, residing at Leonia, in the county of Bergen and State of New Jersey, have invented a new, original, and ornamental Design for an Electric-Light Fixture, of which the following is a specification, reference being had to the accompanying drawing, form part thereof.

In said drawing:

Figure 1 is a plan view of an electric light

fixture embodying my new design. In this figure half of the fixture with the applied ornamentation is shown in full lines and the remaining half in dot and dash lines.

Figure 2 is a side elevation of the same.

I claim:

The ornamental design for an electric light fixture, substantially as shown.

GUSTAVE E. VILLARET.
